UNITED STATES PATENT OFFICE.

SHERMAN W. SCOFIELD AND MARTIN W. MUEHLHAUSER, OF CLEVELAND, OHIO.

MUFFLER.

Application filed October 13, 1919. Serial No. 330,200.

To all whom it may concern:

Be it known that we, SHERMAN W. SCOFIELD and MARTIN W. MUEHLHAUSER, citizens of the United States, residents of Cleveland, county of Cuyahoga, and State of Ohio, have invented new and useful Improvements in Mufflers, of which the following is a specification, the principle of the invention being herein explained and the best mode in which we have contemplated applying that principle, so as to distinguish it from other inventions.

Our invention relates to mufflers, and particularly to a suction muffler adapted for use with internal combustion engines. The invention is designed to provide an apparatus of this character in which the muffling means are self-operated, i. e., the suction-producing means are not positively operated by an extraneous driving power but driven by the pressure of the expanding exhaust gases from the cylinders; in which the muffling action shall be very efficient; and in which the reduction of the power output, due to the baffling action, shall be kept at a minimum.

The annexed drawings and the following description set forth in detail certain means embodying our invention, the disclosed means, however, constituting but one of the various mechanical forms in which the principle of the invention may be employed.

In said annexed drawings:

Figure 1 represents a broken side elevation, of our improved muffler, in combination with fragmentary parts of the cylinders of an internal combustion engine with which the same is connected;

Figure 2 represents a plan view of our improved muffler;

Figure 3 represents a fragmentary horizontal section of a casing within which the suction-creating means are disposed, said means being, in the form of device illustrated, two sets of fan blades, an enlarged diagrammatic view of the same being shown in said figure;

Figure 4 represents, upon an enlarged scale, a longitudinal vertical section, taken in the plane indicated by the line IV-IV, Figure 2, the fan blades being shown in full;

Figure 5 represents a lateral face view of the two sets of fan blades; also a vertical transverse section of the containing casing;

Figure 6 represents a central vertical

transverse section, taken in the plane indicated by the line VI-VI, Figure 4;

Figure 7 represents a fragmentary horizontal section, taken in the plane indicated by the line VII-VII, Figure 6;

Figures 8, 9, 10, 11 and 12 represent different views of a common shaft upon which two sets of fan blades are mounted, only one blade of each set being shown, said views comprising respectively, Figure 8, a side view; Figure 9, a bottom plan view from the plane indicated by the line IX-IX, Figure 8; Figure 10, a plan view from the side opposite to that from which Figure 9 is taken, as indicated by the line X-X, Figure 8; Figures 11 and 12 end elevations, taken from the planes indicated by the lines XI-XI and XII-XII, respectively, Figure 8.

Referring to the annexed drawings, Figure 1, an exhaust pipe from the cylinders of an internal combustion engine is indicated by the ordinal 1, the same communicating with the cylinders 2 and adapted to be connected to a pipe 3 serving as an intake pipe in our improved muffler for the exhaust gases from said cylinders. The muffler proper is contained within a cylindrical casing comprised of the two members 4 and 5 integrally secured together by means of flanges 4' and 5' and suitable bolts, as plainly shown in Figures 2 and 5. This casing is subdivided by means of a partition member 6, the same being a circular plate whose marginal edge is secured between the flanges 4' and 5' of the casing members 4 and 5. This partition member 6 is formed with a central aperture 6' providing communication between the compartments 7 and 8 formed in the casing by said partition member 6. Suitably secured to the inner side faces of the casing are bearing members 9 and 10 within which are journaled the ends of a shaft 11, said shaft intersecting the central aperture 6' of the partition 6. Special lubricating means are provided for the journal ends of the shaft 11, the same consisting of metal 12 within which is imbedded graphite or other suitable lubricating material. The shaft 11 is formed with two enlarged cylindrical hub portions 11', one within each of the compartments 7 and 8. Mounted upon the shaft 11 and secured within these enlarged hub members 11' are two sets of fan blades 13 and 14.

The exact means for mounting the fan blades consist of two series of stems or hold-

ers 13' and 14' integrally secured within said hub members 11' and secured at their outer ends to the rear faces of said fan blades 13 and 14, as plainly shown in Figures 4, 5 and 6. The inner edges of the blades 13 and 14 are tapered, as indicated by 13³ and 14³, Figure 6, and the extreme inner portion of said blades consist of narrow tongue members 13² and 14² disposed in suitable slots 11² cut in the hub members 11', said tongues 13² and 14² extending laterally from said slots and being bent back flush against the side faces of said hub members 11'.

The exhaust gases from the pipe 1 enter the compartment 7 through the inlet pipe 3 and impinge upon the said fan blades 13. These gases leave the casing formed by the members 4 and 5 through the compartment 8, escaping through the outlet pipe 15, Figures 1, 2 and 4. The two sets of fan blades 13 and 14 are set at an angle to the axis of the shaft 11, the set 13 being set at one angle, and the set 14 being set at another angle. These angularities and the relation between them is plainly indicated by the developed view in Figure 3. As shown in Figure 2 the pipes 3 and 15 form tangential inlet and discharge passages, respectively, opening into the compartments 7 and 8 of the muffler through the cylindrical walls 4² and 5² thereof adjacent the top. The exhaust gases are discharged from the engine manifold through the pipe 3 to the compartment 7 of the muffler in intermittent rapidly moving puffs, each of which consists of a body of gas having a high pressure adjacent the forward end thereof and a gradually decreasing pressure from the high pressure point back to the manifold. The forward high pressure portion of each puff impinges against the fan blades 13 in the compartment 7 imparting rotative movement to the shaft 11 which carries the blades 14 in the compartment 8 as well as the blades 13. The inclination of the blades 13 is such as to force the gases toward the partition 6 and maintain a high pressure adjacent said partition to facilitate the movement of the gases into the compartment 8. The inclination of the fan blades 14 is such that the rotary movement caused by the gas stream tends to force the gases away from the partition 6 toward the outer side wall 5 of the compartment 8 and by centrifugal action to discharge the gases through the tangential outlet passage 15. The rotation of the fan blades 15 creates suction through the axial passage 6¹ in through the partition 6 and quickly relieves the initial pressure in the chamber 7 due to the entrance thereto of the high pressure portion of the puff. The passage of the high pressure portion of the puff through the two fans results in the expenditure of a portion of the kinetic energy of the moving gas in rotating the fans and

the momentum imparted to the fans by the high pressure portion of the puff causes a suction in the passage 3 which accelerates the lagging portion of the gas discharge from the engine cylinder and establishes a low pressure in the pipe 3 and manifold at the time when a succeeding puff of gas is discharged from an engine cylinder.

The capacities of the two fans are so proportioned that successive puffs of spent gases from the engine cylinders enter the compartment 7 before the preceding puffs are entirely discharged. The action of the fans is to retard the forward high pressure portion of each puff employing a portion of the kinetic energy thereof to accelerate the movement of the fans, the momentum of the fans due to the passage of the high pressure portion of the puff accelerating the movement of the lagging portion of the puff whereby the successive puffs are discharged in a substantially uniform stream through the passage 15, practically eliminating the noise of exhaust, and whereby low pressure is established in the engine manifold and passage 3 at the instant of each discharge from an engine cylinder, eliminating the back pressure and consequent reduction of power which is an inherent disadvantage in mufflers as heretofore designed.

It has been found that by setting the fan blades 13 and 14 at substantially the angularities shown, the flow of gas through the muffler is properly regulated to effect the results described. However it is to be understood that this exact arrangement of fan blades is not essential to our invention but merely illustrative of that embodiment of our invention which we have found most efficient.

What we claim is:

1. A muffler comprising, in combination with a cylindrical casing provided with an inlet and tangential inlet and outlet passages disposed in different planes perpendicular to the casing axis; a partition disposed in said casing, perpendicular to the axis of the latter, and dividing the same into a pair of compartments, one of the latter communicating with said inlet and the other communicating with said outlet, a shaft rotatably supported in said casing, two sets of fan blades mounted upon said shaft in said compartments, respectively, said fans adapted to be rotated by the exhausting gases, and means providing communication between said compartments, one set of said fan blades being set at different angles, respectively, to the axis of said shaft, the fan blades in the inlet compartment being set at an angle to the axis of said shaft materially greater than the angle at which said outlet compartment blades are set, whereby a suction is created in said inlet compartment and gases are delivered therefrom to said

outlet compartment and also drawn from the inlet compartment and delivered through said outlet compartment to said outlet.

- 5 2. A muffler for use with internal combustion engines comprising a casing provided with an inlet and means directly connecting said inlet with the cylinder exhaust, said casing being formed also with an outlet, a partition disposed in said casing and
- 10 dividing the same into a pair of compartments formed with said inlet and said outlet, respectively, said partition being formed with a centrally disposed opening, a shaft rotatably supported in said casing, and fans 15 mounted upon said shaft in said compartments, respectively.

Signed by us this 9th day of October 1919.

SHERMAN W. SCOFIELD.

MARTIN W. MUEHLHAUSER.
